US00D906437S

(12) **United States Design Patent** (10) **Patent No.:** **US D906,437 S**
(45) **Date of Patent:** **** Dec. 29, 2020**

(54) **COORDINATION TRAINING APPARATUS**

(71) Applicant: **Josh Broeker**, Winter Garden, FL (US)

(72) Inventor: **Josh Broeker**, Winter Garden, FL (US)

(**) Term: **15 Years**

(21) Appl. No.: **29/647,652**

(22) Filed: **May 15, 2018**

(51) **LOC (12) Cl.** **21-01**

(52) **U.S. Cl.**

USPC **D21/468**

(57) **CLAIM**

The ornamental design for a coordination training apparatus, as shown and described.

DESCRIPTION

FIG. 1 is a top left perspective view of the coordination training apparatus showing the new design;
FIG. 2 is a front elevational view of the coordination training apparatus thereof;
FIG. 3 is a rear elevational view of the coordination training apparatus thereof;
FIG. 4 is a left side elevational view of the coordination training apparatus thereof;
FIG. 5 is a right side elevational view of the coordination training apparatus thereof;
FIG. 6 is a top plan view of the coordination training apparatus thereof; and,
FIG. 7 is a bottom plan view of the coordination training apparatus thereof.

1 Claim, 4 Drawing Sheets
